W. Hopkins,
Ship Building

Patented. May 13. 1803.

May 13, 1863

William Hopkins

Letters Posted Space May 13, 1863.

The column reported to me that Captain Palmer and making
part of the same, containing a description in the words of
the said William Hopkins himself of his improvement of
building boats.

All mould is made exactly the form and size of a boat
of crooked timber with spaces between each timber in order
that when boats are built being turned bottom upwards
the timber of the boat are placed at one end and bent over
the mould one after another regularly until the boat is turned
up. Then the plank are bent in in the common manner and
with much more facility, the work being all done on the
boards having also much more ease, then the boat
remaining on the mould may be omitted off crooked and
parts. There being reason of this remains but little to do
to finish the boat which is much stronger built of bent
timbers than in the common manner, which may be often
to much trouble often much easier the grain which makes
them very liable to break, the boat is built upon the
same principles that a crooked timber boat has that is
upon a flat, the timber being bent with stems well bent
with ease and all the trouble of setting up a boat running
on rollers and turning the ship 90° is prevented.
